FOREIGN PATENT DOCUMENTS

GB	2207453 A	2/1989

Primary Examiner — Cynthia Ramirez

Assistant Examiner — Gino Colan

(57) **CLAIM**

We claim the ornamental design for the ladder top, as shown and described.

DESCRIPTION

FIG. 1 is a front perspective view of a ladder top showing our new design;

FIG. 2 is a top plan view thereof;

FIG. 3 is a front elevational view thereof;

FIG. 4 is a rear elevational view thereof;

FIG. 5 is a right side elevational view thereof, shown in a larger scale;

FIG. 6 is a left side elevational view thereof, shown in a larger scale; and,

FIG. 7 is a bottom plan view thereof.

The broken lines shown in the figures are included for the purpose of illustrating portions of the ladder top and form no part of the claimed design.

1 Claim, 5 Drawing Sheets
